TUFTING NEEDLE

Filed Sept. 15, 1947

UNITED STATES PATENT OFFICE

2,610,598

TUFTING NEEDLE

Beatrice H. Midas, Chicago, Ill.

Application September 15, 1947, Serial No. 773,959

4 Claims. (Cl. 112—80)

1

This invention relates to an improved tufting needle for use in producing handmade articles having a fabric base with pile loops of uniform length formed thereon and has as its general object the provision of a simple, compact and efficient tufting needle which may be easily adjusted for forming loops of predetermined, uniform lengths.

Another object of the invention is the provision of a hollow needle element having a longitudinal slot disposable in substantial alignments with the needle slot for threading the needle without removing it from the holder.

A further object of the invention is the provision of a tufting device of the character indicated wherein the needle and holder are provided with longitudinal slots and are rotatable with respect to each other to move said slots out of alignment with each other after threading of the needle in order to retain the yarn securely therewithin against inadvertent displacement.

An additional object of the invention is the provision of a tufting device of the character indicated having a slotted holder and a fixed slotted cylindrical sleeve therewithin, the holder sleeve and needle element having adjustable cooperating means for locking the needle element selectively at any one of a plurality of spaced points therealong in order to vary the effective length of the piercing end of the needle and to produce loops of uniform, predetermined lengths.

The foregoing objects as well as additional objects and advantages of the invention will be readily apparent in the course of the following detailed description taken in connection with the accompanying drawing which illustrates several preferred embodiments of the invention and wherein:

Fig. 1 is a front elevation of the assembled tufting device with the respective slots of the holder, the holder sleeve and the needle element in aligned position for threading the needle.

Fig. 2 is a side elevation of the assembled tufting device.

Fig. 3 is a longitudinal sectional view through the holder and holder sleeve with the needle element removed.

Fig. 4 is a plan view of a blank from which the holder sleeve may be formed.

Fig. 5 is a front elevation of the needle element showing the gauge indentations on the upper portion thereof and the longitudinally extending threading slot.

Fig. 6 is a side elevation of the needle element of Fig. 5.

2

Fig. 7 is a plan view of a blank from which the needle element may be formed.

Fig. 8 is an elevational view of the assembled and threaded device held in operative position by the user.

Fig. 9 is an enlarged cross-section illustrating the needle element in locked position with its threading slot rotated out of alignment with the longitudinal slots in the holder and holder sleeve.

Fig. 10 is a similar view, but with the needle in unlocked, threading position.

Fig. 11 is a fragmentary detail view taken on line 11—11 of Fig. 9.

Fig. 12 is a cross-section of a modified form of locking arrangement involving the use of a set screw having a pointed end engageable against the needle element.

Fig. 13 is a cross-section of another modification of locking arrangement involving the use of locking apertures in the needle element, said apertures being selectively engageable by a set screw threaded into the top of the holder.

Fig. 14 is a plan view of a blank from which the needle element of the modification of Fig. 13 may be formed, the locking apertures being shown on the upper portion thereof.

Referring now to the drawing in greater detail, the needle element 10 is preferably made from a sheet metal blank 11 (see Fig. 7) shaped to provide a substantially cylindrical body portion 12 having a longitudinal slot 12a and a lower piercing portion 13 having a respective longitudinal slot 13a in alignment with slot 12a. The lower end of piercing portion 13 is pointed as shown at 14 for piercing the fabric and an aperture 15 is provided adjacent point 14 to serve as an eye through which the yarn Y passes. Another aperture 16 is provided adjacent the upper end of body portion 12 and in alignment with said lower aperture 15 for feeding the yarn Y into the needle 10.

Body portion 12 of needle element 10 is formed with a plurality of gauge indentations 17 extending circularly thereabouts which serve to adjustably vary the effective length of piercing portion 13 of needle 10 and therefore the lengths of the loops formed on the fabric in a manner to be fully indicated hereinbelow.

A holder 18 is provided for the tufting device having a longitudinal cylindrical bore extending therethrough and a longitudinal slot 18a. Holder 18 is preferably made of light-weight material, such as wood or plastic and is formed with an annular extension 19 to afford a comfortable grip by the tips of the fingers and thumb, as illustrated

in Fig. 8. Holder 18 carries at its top end a collar 20 having a longitudinal slot 20a and a set screw 21 for a purpose to be fully described and a sleeve 22 is fixed within holder 18 and collar 20 in any suitable manner.

Sleeve 22 is preferably made from a sheet metal blank 23 of resilient material formed with a locking or pressure tongue 24 having a transverse projection 24a adapted to selectively engage with in any one of the gauge indentations 17 of needle 10 when said needle is placed within sleeve 22 and fix the effective length of piercing portion 13 between the bottom of holder 18 and eye 15. It is to be noted that sleeve 22 is provided with a longitudinal slot 22a (Figs. 9 and 10) in alignment with slot 18a of handle 18 for permitting the passage of the yarn therethrough in threading needle 10.

The needle 10 is initially placed within sleeve 22 so that threading slots 12a and 13a are in alignment with longitudinal slots 18a, 20a and 22a of the holder 18, collar 20 and sleeve 22 respectively, as clearly shown in Fig. 10. The needle 10 may be threaded by passing the yarn Y through upper eye 16 and lower eye 15, the aligned slots 18a, 20a, 22a of the holder components and 12a and 13a of the needle 10 allowing the yarn to pass inwardly within the bore of the hollow needle when the yarn is tightened. The needle 10 is then rotated within sleeve 22 as shown in Fig. 9 so that the threading slots 12a and 13a thereof will move out of alignment with slots 18a, 20a, and 22a of the holder components and retain the yarn within the tufting device against accidental dislodgment.

In order to fix the effective lengths of piercing portion 13 of needle 10, set screw 21 is turned inwardly against locking or pressure tongue 24 until projection 24a thereof enters a selected gauge indentation 17 on body portion 12 of needle 10 as clearly shown in Fig. 11. As has been previously pointed out, sleeve 22 and locking tongue 24 are of resilient material so that when set screw 21 is loosened to change the effective length of the needle 10, locking tongue 24 will move outwardly away from its engaged indentation 17 on needle 10 to permit resetting of said needle. The presence of upper eyelet 16 through which the yarn passes retains the yarn within the hollow needle 10 at all times.

Fig. 12 illustrates a modified form of locking arrangement and illustrates the collar 30 having slot 30a, the sleeve 31 having slot 31a and the needle 32 having threading slot 32a.

A set screw 33 having a pointed end 34 is threaded through collar 30 and sleeve 31 to engage against the upper portion of needle 32, which needle may be provided, if desired, with gauge indentations similar to those described above for the initial embodiment.

As a further modification, illustrated in Figs. 13 and 14, the needle 40 may be formed from a blank 41 having a plurality of locking apertures 42 in the upper portion thereof and upper and lower yarn eyes 43 and 44 and shaped to form an upper body portion and a lower piercing portion with an aligned threading slot 40a extending longitudinally between said body and piercing portions for the entire length of needle 40. Needle 40 formed in this manner is slidably received within a holder having a sleeve 45 and collar 46. Collar 46 carries a set screw 47 for selectively engaging one of the locking apertures 42 of the needle 40 after threading with yarn and rotating the threading slot 40a thereof out of open align-

ment with respect to slots 45a and 46a of sleeve 45 and collar 46, respectively. Set screw 47 is preferably provided with a stop shoulder 47a for limiting the inward motion of said screw to prevent its entrance for too great a distance within needle 40. The effective length of the piercing portion of needle 40 may be determined by entering set screw 47 within a selected aperture 42 in the upper portion of said needle.

It will be noted that the upper eye 16 is located at the rear or trailing side of the needle diametrically opposite to the slot 12a (which faces the leading side of the needle), hence the weight of the yarn ball tends to guide the yarn supply over the back of the operating hand as well as to restrain the yarn from entering and getting out of the upper part of slot 12a.

Since certain additional modifications may be made in the tufting needle of the invention without departing from the scope thereof, it is intended that all matter contained in the foregoing description and shown in the accompanying drawing be interpreted merely as illustrative and not in a limiting sense.

What is claimed is:

1. A tufting device comprising a hollow cylindrical needle having an upper body portion and a lower piercing portion, a pair of aligned yarn eyes at opposite ends of said needle and aligned longitudinal threading slots in said body and piercing portions; a slidable holder mounted on the body portion of said needle for varying the effective length of the piercing portion of said needle, a sleeve fixed within said holder, said needle being normally freely rotatable within said sleeve, said holder and said sleeve having aligned longitudinal slots disposable in alignment with the threading slots of said needle whereby the threading slots of said needle may be rotated out of alignment with the respective aligned slots of said holder and said sleeve, after threading the needle with yarn to prevent the inadvertent dislodgement of the yarn, a slotted collar fixed at the upper end of said holder with its slot in alignment with the slots in the holder and the sleeve, and a set screw carried by said collar and movable to lock the needle in adjusted position against movement relative to said sleeve and collar.

2. A tufting device in accordance with claim 1 wherein the body portion of said needle has a plurality of locking apertures therealong and said set-screw has selective engagement within any one of said apertures for varying the effective length of said needle.

3. A tufting device in accordance with claim 2, wherein said set screw is provided with a stop shoulder for limiting the inward motion of said screw with respect to the hollow body portion of said needle.

4. A tufting device comprising a hollow cylindrical needle having an upper body portion and a lower piercing portion, a pair of aligned yarn eyes at opposite ends of said needle and aligned longitudinal threading slots in said body and piercing portions, a slidable holder mounted on the body portion of said needle, a sleeve fixed within said holder, said holder and said sleeve having aligned slots disposable in alignment with the threading slots of said needle, said needle being normally freely rotatable within said sleeve, said sleeve having an integral resilient tongue provided with a locking projection, a slotted collar fixed at the upper end of said holder with its slot in alignment with the slots in the holder and

sleeve, and carrying a set screw adapted to bear against said resilient tongue, the body portion of said needle having a plurality of spaced indentations, said locking projection being selectively engageable within any one of said indentations for varying the effective length of the piercing portion of said needle.

BEATRICE H. MIDAS.
